CONTACT ROLL WIPER

Eugene A. Ford, Scarsdale, N. Y., assignor to International Business Machines Corporation, New York, N. Y., a corporation of New York

Application October 14, 1938, Serial No. 234,835

3 Claims. (Cl. 235—61.11)

This invention pertains to analyzing means for analyzing record cards or the like to control accounting or printing apparatus.

In mechanical accounting systems data are recorded on record cards by perforating columns of the record cards in accordance with a selected code to designate the various data. These record cards are then sent through an analyzing means which senses the perforations and controls apparatus in accordance with the data represented by the perforations. The present invention is particularly concerned with an electrical analyzing means which analyzes the record cards while in motion. The electrical analyzing means comprises wire brushes which wipe the surface of the card during movement of the latter and upon encountering a perforation in the card engage through the perforation with a common contact roll, causing an analyzing circuit to be established. During the passage of the card between the analyzing brushes and the contact roll the analyzing brushes tend to remove fuzz from the surface of the card and this fuzz tends to accumulate on the surface of the contact roll. In addition, grit and other dirt may accumulate on the contact roll; the dirt, grit and fuzz tends to interfere with the proper feed of the record card and the proper analysis of the latter.

Accordingly, the main object of the present invention is to provide novel means for cleaning the surface of the contact roll during analysis of the record cards.

It is a further object to provide such a cleaning means as will also serve to conduct current from the contact roll.

More specifically, it is intended to provide a rotary cleaning brush having spirally arranged bristles for progressively engaging the contact roll along its length so as to wipe the entire peripheral area of the contact roll during rotation of the latter, the progressive sweep of the cleaning brush along the length of the contact roll effecting engagement of only one circular portion of the contact roll at one time so as to minimize the friction between the brush and the contact roll.

It is a further object of the invention to provide means for adjusting the pressure of the cleaning brushes against the contact roll.

Further objects of the instant invention reside in any novel feature of construction or operation or novel combination of parts present in the embodiment of the invention described and shown in the accompanying drawings.

In the drawings:

Fig. 1 is a vertical sectional view through the feeding, analyzing, and printing means of the machine.

Fig. 2 is a side view of the drive for the cleaning brush;

Fig. 3 is a section taken substantially along lines 3—3 of Fig. 1;

Fig. 4 is a detail perspective view of a portion of the cleaning brush;

Fig. 5 is a circuit diagram of the analyzing means; and

Fig. 6 is a detail front view of a portion of the cleaning brush assembly.

While the invention is of general application to record sheet or card feeding means and to statistical card or sheet analyzing means, it is preferred for the purposes of the disclosure to explain and illustrate the invention in connection with an electrical analyzing means for analyzing the cards while in motion. Particularly, the invention is shown in connection with the analyzing and printing means of the machine disclosed in Patent No. 2,076,713.

Referring to Fig. 1, a stack of record cards T to be analyzed is placed in a supply hopper 10. The cards are fed one at a time from the supply hopper by means comprising a picker knife 11 carried by a slide 12 which has a swivel connection to a rocker arm 13. Rocker arm 13 is oscillated by a link connection 14 from a crank arm 15 of a shaft 16. Each revolution of shaft 16 effects a reciprocation of arm 13 and connected slide 12 to cause the picker knife 11 during its forward stroke to feed the bottom card out of the supply hopper 10 and into the grip of a pair of continuously rotating feed rolls 17. The feed rolls 17 continue to feed the card through suitable guideways and between a feed roll 18 and the contact roll 20. During its travel between feed rolls 17 and the feed roll 18, the card moves over one arm of a card lever 19 to close card lever contacts 50, the closure of which is necessary to enable analyzing circuits to form as will be brought out later. As the forward edge of the card passes feed roll 18, it moves between the surface of the contact roll 20 and an upper guide and shield plate 21 which constrains the card to follow the upper quadrant of the periphery of the contact roll. A lower guide shield 22, the upper edge of which is spaced from the lower edge of upper guide plate 21, continues to guide the card around the contact roll and into the grip of a pair of eject rolls 23 which eject the card to a delivery hopper 24.

Feed roll 18 is grooved and between the grooves the analyzing brushes 25 extend into engagement with the contact roll 20. During feed of a card on contact roll 20, the card keeps the analyzing brushes 25 out of engagement with the contact roll until a perforation in a card is sensed by an analyzing brush whereupon the brush engages with the contact roll through the perforation to form an analyzing circuit. In accordance with 10 the analyzing circuits which result from sensing of the perforations of a card column, print magnets 26 are energized to control the setting of a type bar 27 thereby locating one of the type elements 28 of the type bar in printing position. 15 This printing position is opposite the gap left between the guide shields 21 and 22. After analysis of the record card, an imprint is made on the record card itself by the type element in printing position, this imprint interpreting or giving a conventional indication of the analyzed perforations. 20 The printing operation is effected by a plunger 29 carried by a slide 30 which is actuated once each cycle by a cam 31 carried by a shaft 32. The slide 30 is positively retracted by a bell crank 25 lever 33 oscillated each cycle by a cam depression 34.

Shaft 32 carries a pulley 36 which through a belt 37 drives a pulley 38 loosely mounted on a shaft 39.

Shaft 39 carries a gear 40 meshed with a gear 41, of insulating material, fixed to a shaft 42. Shaft 42 is rotatably carried at opposite ends by the lower ends of dependent arms 43, the upper ends of which are fixed to shaft 39. The bearings 35 for shaft 42 include outer collars 43' of insulating material which serve to insulate the shaft from the arms 43. The gear 41, also being of insulating material, insulates shaft 42 and the parts carried thereby from the shaft 39. The purpose of thus insulating shaft 42 is to enable 40 the cleaning brushes 46 carried thereby to serve as conductors for connecting the contact roll 20 into the analyzing circuits, as will be described further on.

Fixed to a central portion of shaft 39 is a dependent arm 43a to the lower end of which is connected one end of a coil spring 43b, the opposite end of which is connected to the frame standard F. Threaded into frame F is a screw 43c, the forward end of which abuts the back of dependent arm 43a. The screw 43c may be adjusted to change the angular position of arm 43a thereby changing the angular position of shaft 39 and of arms 43 which carry shaft 42. The screw 43c is maintained in an adjusted position by a lock nut 43d. The spring 43b serves to maintain arm 43a firmly against the forward end of screw 43c. The purpose of the angular adjustment of arm 43a is to bring the shaft 42 50 closer or further from the contact roll 20 thereby providing for greater or less pressure of the cleaning brushes 46 carried by the shaft against the peripheral surface of the contact roll. Shaft 42 is knurled, as indicated in Fig. 6, and carries a plurality of duplicate metal rings 44 spaced apart by washers 45. Each ring is formed at diametrically opposite sides with tangentially directed clips 44' each of which rigidly anchors one end of a conductive, cleaning brush 46, each 55 brush being made up of a plurality of wire bristles located side by side and engaging the inner flat side of the clip 44', so that the unanchored length of the brush is restrained from moving outwardly of the clip. Each brush 46 extends in 60 a tangential direction and is free to flex inwardly

towards the shaft 42. The knurls of shaft 42 tend to prevent rotation of the rings 44 and washers 45 relative to the shaft, but in order to maintain these elements more positively against rotative displacement, collars 47 and 48 are secured to the shaft 42, as indicated in Fig. 3, to straddle the assembly of rings and washers. The collars 47 and 48 are adjusted to clamp the rings and washers closely together so as to prevent their rotative displacement with respect to the shaft. 10

The ring elements 44 and brushes 46 are duplicate elements, but offset around the shaft 42 so as to provide four spirally arranged rows of brushes 46, which may be distinguished as rows A, B, C, and D. The spiral arrangement is obtained as follows: Each ring 44 is set on shaft 42 so that its pair of diametrically opposite brushes 46 is displaced 90° clockwise relative to the pair of corresponding brushes of the ring directly below, as viewed in Fig. 3. Further, each alternate ring 44 is set on shaft 42 so that its pair of brushes are slightly displaced clockwise relative to the pair of brushes of the preceding alternate ring, also below as viewed in Fig. 3. Thus, one alternate set of rings 44 is set so that its brushes form two diametrically opposite spiral rows A and C of brushes 46 and the intermediate, alternate set of rings 44 is set so their brushes provide the intermediate diametrically opposite spiral rows B and D of brushes. The extent of displacement of the adjacent brushes of a row A, B, C, or D is such that a clockwise angle (as viewed in Fig. 4) of slightly less than 90° is provided between the first brush of the row and the last. 20

The movement of the cleaning brushes is as follows, assuming the first brush of a row A is engaging the contact roll 20. An increment of counterclockwise rotation (as viewed in Fig. 1) of shaft 42 brings the first brush A below and out of engagement with the contact roll 20 and brings the next brush of row A into engagement with an axially spaced portion of the contact roll. Successive increments of such rotation, successively bring the spaced brushes of row A into engagement with the confronting portions of the contact roll, so that at the end of slightly less than 90° of rotation, the last brush of row A is engaged with the contact roll. Thus, row A has swept progressively along spaced portions of the width of the contact roll facing the brushes of row A. The next increment of rotation brings the first brush of row B into engagement with the contact roll and at the end of nearly 90° of such rotation the last brush of row B engages the 55 contact roll. The brushes of row B thus progressively sweep along spaced portions of the width of the contact roll facing the brushes of row B. Since the brushes of row B are displaced axially relative to the brushes of row A, row B will sweep portions of the width of the contact roll intermediate the portions of the width swept by row A. After the last brush of row B has swept the contact roll, the first brush of row C engages the contact roll. At the end of nearly 60 90° further rotation, the last brush of row C engages the contact roll. The next increment of rotation carries the first brush of row D into engagement with the contact roll. After nearly 90° of rotation, the last brush of row D engages the 70 contact roll. The next increment of rotation brings the first brush of row A again into engagement with the contact roll, completing the circuit of action of brushes 46 of rows A, B, C, and D. The brushes of row C wipe portions along 75

the width of the contact roll circumferentially aligned with the portions wiped by brushes A, and likewise the wiping action of the brushes of rows B and D is along circumferentially aligned portions of the contact roll. It may be understood from the above explanation, assuming the first brush of row A engaged with the contact roll, that at the end of the first 90° of rotation, the first brush of row B is brought into engagement. At 10 the end of the next 90° of rotation, the first brush of row C is engaged with the contact roll. At the end of the third 90° of rotation, the first brush of row D is brought into engagement, and at the end of the fourth 90° of rotation, or a 15 complete 360° of rotation of shaft 42, the first brush of row A again is engaged with the contact roll. The same circuit is effected for the second, third, and so on, brushes of rows A, B, C, and D. The brushes of rows A, B, C and D thus sweep the 20 contact roll during rotation of the latter, bare of fuzz, grit, and dirt.

The contact roll 20 is positively driven counterclockwise (as viewed in Fig. 1) by means not shown here but described in aforementioned 25 Patent No. 2,076,713. The cleaning brush device is also positively driven counterclockwise (as viewed in Fig. 1) by shaft 32, through pulley 36, belt 37, pulley 38, and gears 40 and 41. Consequently, the portion of the cleaning device engaged with an area of the contact roll is moving 30 in a direction tangentially opposite to the direction of movement of the engaged area of the contact roll. As a result, the cleaning brushes 46 throw the fuzz, dirt, and grit positively away from the contact roll, as well as 35 from the cleaning brushes. Were the cleaning brushes and the contact roll to move in opposite rotational directions, that is, were the cleaning device to rotate clockwise and the contact roll counterclockwise, the engaging portions of 40 the cleaning device and contact roll would move in the same linear direction and the cleaning brushes would not tend to throw the fuzz and dirt or grit away from the contact roll. As a 45 further consequence, the fuzz, dirt, and grit removed from the contact roll would tend to accumulate on the upper surfaces of the cleaning bristles or strands. Thus, the advantages of 50 positively rotating the cleaning device in a direction such that the engaging portions of the cleaning device and the contact roll move in opposite linear directions are that the brushes 46 sweep the fuzz, grit, and dirt away from the 55 periphery of the contact roll and also away from the cleaning brushes. The progressive sweep of the cleaning brushes across the contact roll provides for engagement of only a portion of the contact roll at a time, so that the frictional resistance to rotation of the contact roll is held to a minimum. Further, the brushes 46 are 60 adjusted into proper engagement with the contact roll by adjustment of shaft 42 to or from the contact roll, this adjustment being effected by adjusting screw 43c, as previously explained.

In addition to brushes 46 acting to clean the contact roll, they also serve to conductively connect the contact roll into the analyzing circuit, as may be understood from Figs. 3 and 5. Any suitable means may be provided to carry current 65 to the brushes 46. One such simple means is shown in Fig. 3 as comprising a conductive brush 47' wiping collar 47 which is fast to shaft 42

carrying the brush holders 44, the three latter elements being of conductive material. Thus, upon an analyzing element engaging, through a perforation in the card, with the contact roll, an analyzing circuit is formed as follows (Fig. 5): 5

Analyzing circuit.—From the left side of the line, through card lever contacts 50, the timing commutator TC, brush 47', the brush 46 engaged with the contact roll 20, through the contact roll, analyzing element 25, a plug connector 51, 10 print magnet 26, and to the opposite side of the line.

A combination of such circuits, as described in Patent No. 2,076,713 energizes magnets 26 to position a type element 28 for printing on the 15 card after its analysis. The printing is effected in the manner previously explained.

While there has been shown and described and pointed out the fundamental novel features of the invention as applied to a single modification it will be understood that various omissions and substitutions and changes in the form and details of the device illustrated and in its operation may be made by those skilled in the art without departing from the spirit of the invention. It is the intention, therefore, to be limited only as indicated by the scope of the following claims.

What is claimed is:

1. In a machine for operating on records bearing designations; the combination of electrical analyzing means for analyzing the designations, said analyzing means including a rotatable contact roll, over which the records travel during their analysis and a device engaging the contact roll for conducting current thereto, said device comprising a spiral row of conductive cleaning brushes extending along the width of the contact roll, and means for rotating said device to progressively sweep the brushes across the width of the contact roll, whereby the brushes serve to conduct current to the contact roll and also to clean the contact roll during rotation of the latter and of the device. 30

2. In a machine of the class described; a 45 cleaning brush for a contact roll, comprising a shaft parallel to the contact roll, and a ring carried by the shaft and formed with diametrically opposite clip portions, a brush anchored at one end to each clip portion to extend in a 50 tangential direction opposite to the tangential direction in which the brush anchored to the other clip extends, and means for rotating said shaft to wipe the brushes in succession across the periphery of the contact roll. 55

3. A device for cleaning a rotatable contact roll comprising a plurality of cleaning brushes, a shaft carrying the latter, means for rotating said shaft to wipe the brushes across the periphery of the contact roll to clean the latter, bail arms carrying the shaft, a rockable bail rod rigidly carrying the arms, and means for rocking the arms to bring the shaft closer or further from the contact roll so as to regulate the pressure of the cleaning brushes against the contact roll comprising a member rigidly extending from the bail rod, an adjusting screw abutting said member and adjustable to rock the bail rod, arms, and shaft positively towards the contact roll, and a spring connected to said member for holding the latter against the adjusting screw. 60 65 70
